(57) CLAIM

The ornamental design for a detachable card pulling apparatus with ribbed gripping portion, as shown and described.

DESCRIPTION

FIG. 1 is a front elevational view of a detachable card pulling apparatus with ribbed gripping portion showing my new design;

FIG. 2 is a right side elevational view thereof;

FIG. 3 is a top plan view thereof;

FIG. 4 is a bottom plan view thereof; and,

FIG. 5 is a perspective view thereof.

The broken line showing of a card is for illustrative purposes only and forms no part of the claimed design.
